UNITED STATES PATENT OFFICE

2,416,569

ELECTRIC CIRCUIT INTERRUPTER OF THE
PLUG-IN TYPE

Alfredo Cianchi, Hemel Hempsted, England

Application January 2, 1943, Serial No. 471,161
In Great Britain December 2, 1941

7 Claims. (CL. 200—112)

1

This invention relates to an electric circuit interrupter such as switch or fusible cutout, of the plug-in type having relatively fixed and movable portions bearing cooperating contact elements.

The invention has for its primary object to provide an improved practical construction of interrupter of this type in the form of a compact unit suitable for mounting either alone or in conjunction with other similar units in a confined space, the arrangement being such as greatly to simplify manufacture, and therefore also cost, without impairing the efficiency of operation of the interrupter.

A more detailed object of the invention is to provide an improved plug-in type interrupter employing a mercury or other enclosed switch whose contact operation is controlled by an electromagnet external to the envelope of the switch, wherein the parts are so arranged as to facilitate inspection and maintenance and to ensure satisfactory operation. This object is achieved according to one feature of the invention by mounting the switch on the relatively movable portion of the interrupter and the electromagnet (or at least the main part thereof) on a separate member detachably mounted in a casing constituting the relatively fixed portion of the interrupter, the arrangement being such that the act of plugging-in not only brings the main contacts into engagement but also brings the switch into the correct operative position in readiness for operation by the electromagnet.

A further object of the invention is to provide an improved plug-in type interrupter employing a fusible cut-out as its main interrupting element, wherein again the parts are so arranged as to facilitate inspection and maintenance, and more particularly to simplify replacement of the fuse element.

Another object of the invention is so to construct a plug-in type interrupter as to enable standard parts to be employed in the relatively fixed and movable portions, either with an electromagnetically operated enclosed switch or with a fusible cut-out, as may be desired.

Yet another object of the invention is to provide improved main contact arrangements in a plug-in type interrupter, which will minimise the risk of damage to a mercury or other switch enclosed in a fragile envelope or of bad contact engagement resulting from shock or vibration.

Still further objects of the invention will be apparent from the appended claims and from the

2

following description of the accompanying drawings, in which

Figures 1, 1a and 1b together constitute an exploded view of a preferred construction according to the invention, Figure 1 being a vertical section on the line I—I of Figure 2, Figure 1a a side elevation of the detachable inner member, and Figure 1b a vertical section on the line II—II of Figure 6.

10 Figures 2 and 3 are respectively a front view and a horizontal section on the line III—III of the fixed casing shown in Figure 1.

Figure 4 is a front view of the detachable inner member shown in Figure 1a, the magnetic core being omitted.

Figure 5 is a vertical section through one half of the member shown in Figure 4.

Figure 6 is a back view of the movable cover shown in Figure 1b.

20 Figure 7 shows in plan the magnetic core belonging to the inner member shown in Figures 4 and 5.

Figures 8 and 8a together constitute a partial exploded view of an alternative construction, Figure 8 showing the inner member in side elevation, whilst Figure 8a is a longitudinal section similar to that of Figure 1b through the cover.

Figure 9 is a horizontal section on the line IX—IX of Figure 8a.

30 Figure 10 shows in vertical section similar to that of Figure 8a another modified form of cover.

Figure 11 is a horizontal section on the line XI—XI of Figure 10.

35 Figures 12 and 12a together constitute a partial exploded view, similar to that of Figures 8 and 8a of a further alternative.

Figures 13 and 13a together constitute an exploded sectional view similar to that of Figures 1, 1a and 1b of an arrangement employing a fusible cut-out.

Figure 14 is a front elevation of the cut-out member detached from the cover of Figure 13a, and

45 Figures 15, 15a and 15b together constitute an exploded sectional view similar to that of Figures 1, 1a and 1b of yet another arrangement.

In the construction of Figures 1 to 7, the fixed portion of the interrupter comprises a casing A of moulded or other insulating material in the form of a narrow box of generally rectangular shape of suitable length and depth open at one of its edges. The casing is mounted with its length vertical and its open edge at the front.

Within the casing A near the top and bottom,

insulating barriers A¹ are formed integral with the casing walls, thus providing small compartments within which the fixed contact elements are mounted. Each of these elements consists of a metal block B preferably with spring contact fingers B¹ at its sides. Holes A² are provided through the top and bottom walls of the casing for the connection of the two fixed contact elements to the main circuit controlled by the interrupter.

The movable portion of the interrupter comprises a cover C of moulded or other insulating material so shaped as to form a handle which can be readily gripped by the fingers to facilitate plugging into and withdrawing from the fixed portion, the cover being of a size to fit over the open front of the fixed casing A. Short insulating walls C¹ project from the back of the cover to give protection for the fragile mercury switch D, which is housed within the trough thus formed at the back of the cover. The movable contact elements which cooperate with the fixed contact elements in the casing A are mounted at the top and bottom of the back of the cover C, and each consists of a pair of flat blades E engaging between the contact block B and the spring fingers B¹ of the corresponding fixed contact element. This simple contact arrangement is adequate for cases where the interrupter has only to deal with relatively light currents and is not likely to be subject to vibration or shocks in use, the natural springiness of the contacts providing sufficient contact pressure and frictional grip for such cases, whilst yet permitting removal of the cover without shock likely to damage the mercury switch. A positive contact locking engagement may however be provided, as will be described later with reference to Figures 8 and 9, especially in heavy current interrupters or interrupters liable to be subjected to vibration in use.

Each movable contact element is provided with a terminal fitting E¹, to which can be attached one of the terminals D¹ of the mercury switch D (or other switch) which constitutes the main member of the interrupter. Whilst other fastening means may be provided to hold the mercury switch in position, it will usually suffice to rely on the terminal attachments for this purpose, and it is preferable to provide some degree of flexibility in the mounting to prevent damage to the switch envelope during handling. In the example illustrated rubber buffer rings D² are provided around the envelope in suitable positions, the cover C and insulating walls C¹ being slightly grooved to receive the edges of the rings D².

The mercury switch D itself is of the type operated by an external electromagnet, and in the example shown has a plunger D³ of magnetic material within the envelope moved on energisation or deenergisation of the electromagnet to displace the mercury and thereby to make or break the circuit. Other forms of enclosed switch operated by an external electromagnet may be employed, if desired. A small window C² is preferably provided in the cover to permit the switch to be viewed from the front, so as to determine whether the circuit is open or closed.

The electromagnet comprising a magnetic core F and a coil F¹ is carried by an inner member G which is normally housed within the fixed casing A but is detachable therefrom. This inner member G consists of a framework of moulded or other insulating material shaped to fit into the central compartment of the fixed casing A between the insulating barriers A¹ and is formed

in two equal parts which fit together to form a closed flat box containing the coil F¹, whose individual winding turns thus lie more or less in planes parallel to the length of the casing A. Co-operating studs and holes G¹ serve to locate the two parts of the member G in their correct relative positions. The inner member G has a central rectangular opening G², which registers with the central hole through the core F¹ and through which the magnetic core F passes, the core being generally U-shaped (as above in Figure 7) with its base passing through the holes in the member G and in the core. The core is made up of a stack of flat laminations, each lying horizontally, and for ease of assembly, each lamination is formed in two parts, as indicated in Figure 7, one part being L-shaped and the other straight. By stacking these L-shaped and straight lamination parts alternately in two L-shaped stacks and forcing the two stacks into interleaved relationship within the central holes, a compact U-shaped core can be built up to fit snugly into the holes in proper position relatively to the coil F¹, the free ends of the laminations adjacent to the pole pieces F³ being bolted together by pairs of bolts F². The sides of the framework of the inner member G are recessed slightly at G³ for the reception of the inner edges of the core F, and the side walls of the casing A are shaped to afford recesses A³ for accommodating the parts of the core projecting from the sides of the inner member G. When the complete inner member is inserted in the casing A and the cover C is plugged into the casing, the pole pieces F³ come close one on either side of the mercury switch D in proper position for the operation thereof when the coil is energised.

At its lower end, the framework G has two grooves G⁴ for the reception of metal terminal bars H, and a deep slot G⁵ is cut through in each half from the central compartment housing the coil F¹ to the corresponding groove G⁴ for the passage of the leads from the two ends of the coil to the two bars H. One of these leads passes direct from the coil to the terminal bar, the necessary contact being obtained by folding the wire along the base of the groove and then clamping the terminal bar down tightly against the end of the wire. The other lead from the coil is taken to one of a pair of spring clips H¹ fitted into the inner member G near the top, these clips serving to hold a small fuse H² in a compartment G⁶ at the top of the member. The other spring clip H¹ is connected by a lead passing through the interior of the member to the second terminal bar H. The coil F¹ is thus connected in series with the fuse H² between the two terminal bars H. The purpose of this small fuse H² is to prevent damage to the mercury switch D resulting from the flow of excessive current through the coil F¹, due for instance to inadvertent connection of the coil terminals to an incorrect voltage supply. The inner member G is preferably provided with a pocket (not shown) for the reception of a spare fuse.

The fixed casing A is provided with pairs of holes, which can be alternatively used for the external connections to the coil terminal bars H in accordance with convenience. Thus one pair 70 of holes A⁴ is provided in the bottom end wall of the casing, and another pair A⁵ in the back wall, whilst the two holes of a third pair A⁶ pass respectively through the two side walls of the casing, this third pair being especially convenient for instances in which two or more interrupters

are mounted side by side with their coils connected in series with one another for simultaneous operation of all the mercury switches, as for example on polyphase circuits having one switch in each phase.

The inner member G and the interior of the casing A are preferably so shaped as to prevent the member from being inserted the wrong way round in the casing, that is with the coil terminals H at the top and the fuse H² at the bottom. Similarly the cover C is provided at one end only with a small stud C³ which fits within a recess A⁷ in the casing wall, thus preventing the cover from being plugged in upside down. Recesses A⁸ are formed in suitable positions in the casing walls to give clearance for the switch terminal connections D¹ and terminal fittings E¹.

As mentioned above, it is sometimes desirable to provide means for locking the main contacts closed, for example to ensure good contact engagement in heavy current installations or to prevent accidental loosening of the contacts in cases when the interrupter is subjected to vibration or to severe shocks, and one convenient arrangement for this purpose is illustrated in Figures 8 and 9, which also serve to show a further variant in which the magnetic circuit of the electromagnet is in two parts respectively on the fixed and movable portions of the interrupter. Figure 8 shows an exploded view of this arrangement, analogous to that of Figure 1, but the fixed casing is omitted from the drawing since it is identical with that shown in Figure 1.

In this arrangement each movable contact element on the cover C consists of a flat strip J bent into the form of a U so as to form two blades engaging between the contact block B and the spring fingers B¹ of the fixed contact element, the strip J being fairly rigid with only relatively slight flexibility. The element is attached to the cover C by means of a screwthreaded bolt J¹ engaging in a tapped hole in the base of the U, this bolt having a small hand lever J² in front of the cover C to facilitate tightening and loosening as required. The two corner edges of the base of the U bed against upstanding knife edges J³ on a small metal plate J⁴ disposed on the back face of the cover C, and it will be clear that with this arrangement tightening of the bolt J¹ will deform the element J so as to force the free ends of the limbs of the U towards one another and into tight engagement with the fixed contact block B, whilst loosening will allow them to open out to their natural parallel position.

The two small hand levers J² are operated to loosen the bolts J¹ when it is desired to withdraw the movable portion from the fixed portion, and they may be so mounted that the act of gripping the main handle of the cover itself operates them to effect loosening of the bolts, the bolts being likewise left loose for the operation of plugging-in. The fixed contact elements on the fixed portion are so arranged that so long as the bolts J¹ are loose and the moving contact blades J are in their natural parallel position the movable portion can be readily and easily plugged in and withdrawn without shock. The small hand levers J² are however operated to tighten the bolts J¹, when the movable portion has been plugged in, so as to force the two blades J of each movable contact element towards one another and thereby to cause them to exert a locking pressure against the contact block B of the fixed contact element. In this way the movable portion is frictionally locked in its plugged-in po-

sition, and good electrical contact ensured. If desired, the two blades J of each movable contact element and the cooperating parts of the fixed contact element may have ribbed or roughened surfaces or may be slightly curved or bent to provide a positive locking action when the locking bolt J¹ is tightened without relying wholly on friction. This arrangement thus allows good electrical contact to be obtained, whilst still permitting free and easy removal of the movable portion when desired.

The inner member G is arranged exactly as in the construction of Figures 1 to 7, except that the magnetic core of the electromagnet is divided with its pole pieces carried by the cover C and only the main U-shaped part of the core carried by the inner member G. Thus the limbs of the main part K of the core are shorter and carry pairs of spring blades K¹ of magnetic material which make contact with the pole pieces K², these pole pieces being secured to the cover C in their proper operative positions relative to the mercury switch D. Thus on plugging the cover C into the fixed casing A, the main electrical circuit is completed at the main contacts and at the same time the magnetic circuit of the electromagnet is completed by engagement of the blades K¹ with the pole pieces K².

Figures 10 and 11 show a modification in the mounting of the mercury switch D on the cover between the insulating walls C¹ at the back thereof, in order to relieve the switch more effectively from risk of damage due to shocks. In this modification the switch is provided at its ends with metal terminal caps L, which are connected by flexible leads L¹ to the electrical terminals of the switch and also by light springs L² to the ends of the envelope. Protective sheaths L³ of insulating material are provided which fit over the ends of the envelope and may if desired extend for the whole length of the envelope, and these sheaths act as guides to limit the movements of the metal terminal caps L relatively to the envelope. The terminal caps L themselves constitute the connections from the switch to the main contact elements on the cover and various alternative clamping arrangements may be provided to ensure proper contact engagement between the caps and the elements. In the example illustrated the contact elements L⁴ are made U-shaped with the base of the U of saddle shape, so that the terminal caps L are held between such saddles and the main body of the cover C to which the contact elements are attached.

The switch carried by the cover may be of the "latch-in" type, that is of the type in which the switch when once closed by the energisation of the electromagnet is held latched in the closed position after the electromagnet has been de-energised, a separate "tripping" electromagnet being provided for releasing the latch and opening the switch. Figure 12 shows the cover and inner member for such an arrangement, these parts cooperating with a fixed casing of the kind shown in Figures 1 to 3. In this arrangement, the cover C is arranged in the manner described above, except that the switch D itself is in this instance of the latch-in type. The inner member differs from that above described in that there are two electromagnets, two sets of terminals and two fuses instead of one. Thus the inner member consists of a moulded framework M formed in two parts which fit together to form a central compartment housing a closing coil N and a tripping coil O, the two coils being located

side by side with their central openings registering with the ends of an aperture M^1 in the wall of each part of the framework. The two coils N and O are respectively linked with two magnetic cores N^1 and O^1 each arranged in substantially the manner described with reference to Figure 7. At each end of the framework, there are a small compartment containing a fuse N^2 or O^2 and also a pair of grooves M^2 for holding terminal bars N^3 or O^3 . Thus one lead from the closing coil N passes to the fuse N^2 and thence to one of the two terminal bars N^3 , whilst the other lead from the coil N goes to the other terminal bar N^3 , with similar connections from the tripping coil O at the other end. The arrangement of these parts will be clear from the description already given with reference to Figures 1 to 7. The fixed casing A is bored with additional holes A^4 or A^5 or A^6 at its other end for the circuit connections from the additional electromagnet.

With such an arrangement (as also sometimes with the other arrangement) it is desirable to provide an interlocking device (not shown) to prevent the cover C from being withdrawn from the casing A except when the switch is open. Such device may consist of a sliding bolt which is moved to its latching position when the closing coil is energised and to its open position when the tripping coil is energised. In some instances it may also be desirable to provide a short-circuited winding on each pole of the electromagnet core or cores in the well-known manner to prevent chattering."

The main member of the interrupter, instead of being in the form of a mercury or other enclosed switch, may consist of a fusible cut-out connected between the movable contact elements, and it is especially convenient for the fixed casing A and the movable cover C to be of such construction that they can be employed, at will, either with a switch as above described or with a fusible cut-out, the inner member used in the case of the switch being removed in the latter event and the space thus vacated occupied by a fitting containing the cut-out and a magazine for the renewal of the fuse link of the cut-out.

Figures 13 and 14 show the interrupter of Figures 1 to 7 adapted for use with a cut-out. In this arrangement the fixed casing A and the cover C are identical with the corresponding parts of the arrangement of Figures 1 to 7, but the inner member G and the mercury switch D are replaced by a two-part moulded fitting P which fits between the insulating walls C^1 of the cover and is suitably anchored thereto. This fitting P contains two compartments, one of which P^1 contains a reel P^2 rotatably mounted on a pivot pin P^3 mounted in the fitting. This reel P^2 has fuse wire wound on it to constitute a magazine for the renewal of the fuse link, the wire from the reel passing out from the magazine chamber through a small end hole P^4 . The second compartment P^5 is of stepped cylindrical construction and houses concentric cylinders of refractory insulating material through which the fuse-link passes. Thus the fuse-link may consist of a length of the wire already drawn off the magazine reel P^2 , passing through a tube P^6 of asbestos within an outer steatite tube P^7 , the free end of the fuse wire being attached to the terminal fitting E^1 on one of the contact elements whilst the part of the wire leading from the fuse to the magazine reel is looped around the other terminal fitting E^1 and clamped thereby. Re-

newal of the fuse wire, when necessary can then be effected very simply by pulling out a suitable length of wire from the reel and attaching a loop of it and also its free end to the two terminals E^1 .

In cases where it is preferred to employ a cartridge fuse, the magazine chamber P^1 can contain one or more spare fuses instead of the magazine reel.

Figure 15 shows a further variant in which the main member of the interrupter comprises a mercury switch Q and a fusible cut-out in series, the latter being mounted in a fitting Q^1 arranged in the manner just described with reference to Figures 13 to 14. The fixed casing A and cover C are each made long enough to accommodate the switch and cut-out one above the other, but otherwise are arranged generally in the manner above described, the cover carrying an intermediate terminal block Q^2 through which the switch and cut-out are connected together.

What I claim as my invention and desire to secure by Letters Patent is:

1. An electric circuit interrupter of the plug-in type, including in combination a relatively fixed casing of generally rectangular shape, relatively fixed contact elements mounted on the casing near its ends, an inner member detachably mounted within the casing between such contact elements, an electromagnet having a coil and a core at least the main part of which is carried by the inner member, a cover movable relatively to the casing, relatively movable contact elements cooperating with the relatively fixed contact elements and carried by the cover near its ends, and an enclosed switch housed within the cover between the relatively movable contact elements and having its terminals connected to such elements, the arrangement being such that when the two relative portions are plugged together with the cooperating contact elements in engagement the switch is connected in circuit through the contacts and is brought into operative relationship with the electromagnet core, contact operation of the switch being controlled by the electromagnet.

2. An electric circuit interrupter, as claimed in claim 1, in which the magnetic core of the electromagnet is generally U-shaped with its plane transverse to the length of the casing when the inner member is in position therein, whilst the coil extends around the base of the U with its plane longitudinal with respect to the casing.

3. An electric circuit interrupter as claimed in claim 1, in which the inner member comprises a compartment housing the electromagnet coil, terminals at at least one end of the member, and means for connecting the ends of the coil to such terminals, and the relatively fixed casing is provided with an insulating barrier for separating such terminals from the relatively fixed contact elements.

4. An electric circuit interrupter as claimed in claim 1, in which the inner member comprises a box-like insulating framework formed in two interfitting parts and containing the electromagnet coil within it, means for supporting the electromagnet core, such core being generally U-shaped with its base passing through the coil and the side walls of the framework and its limbs projecting laterally beyond such side walls, terminals at one end of the framework, and means for connecting such terminals to the ends of the coil, the casing and the inner member having such asymmetrical shapes that the latter can

only be inserted into the casing in one way with its terminals always lying at the same end of the casing and insulated from the relatively fixed contact element at such end of the casing.

5. An electric circuit interrupter of the plug-in type, including in combination a relatively fixed casing of generally rectangular shape, relatively fixed contact elements mounted on the casing near its ends, an electromagnet housed within the casing and having a generally U-shaped magnetic core with its plane transverse to the length of the casing and a coil extending round the base of the U with its plane longitudinal with respect to the casing, a cover movable relatively to the casing, relatively movable contact elements cooperating with the relatively fixed contact elements and carried by the cover near its ends, and a mercury switch housed within the cover between the relatively movable contact elements and having its terminals connected to such elements, the arrangement being such that when the two relative portions are plugged together with the cooperating contact elements in engagement the switch is connected in circuit through the contacts and is brought into operative relationship with the electromagnet core, contact operation of the switch being controlled by the electromagnet.

6. An electric circuit interrupter of the plug-in type, including in combination a relatively fixed casing of generally rectangular shape, relatively fixed contact elements mounted near the ends thereof, a cover movable relatively to the casing, relatively movable contact elements cooperating with the relatively fixed contact elements and carried by the cover near its ends, and a main circuit interrupting device carried by the cover and connected between the relatively movable contact elements, at least one of the relatively movable contact elements consisting of a flat strip bent into the form of a U, a pair of knife edges

against which the base of the U-shaped strip abuts, and a clamping device which acts on the base of the strip between the knife edges and when operated forces the base more tightly into engagement with the knife edges and thereby causes the limbs of the U to exert a gripping pressure on the relatively fixed contact element engaging between such limbs.

- 5 7. An electric circuit interrupter as claimed in
 10 claim 1, in which each of the relatively movable contact elements consists of a flat strip bent into the form of a U, a pair of knife edges against which the base of the U-shaped strip abuts, and a clamping device which acts on the base of the strip between the knife edges and when operated forces the base more tightly into engagement with the knife edges and thereby causes the limbs of the U to exert a gripping pressure on the relatively fixed contact element engaging between such limbs.
